UNITED STATES PATENT OFFICE.

MOSES C. ABUZA, OF BROOKLYN, NEW YORK, ASSIGNOR TO ARFLEX LAMP AND FIXTURE M'F'G. CORP., OF BROOKLYN, NEW YORK, A CORPORATION OF NEW YORK.

DESIGN FOR A BODY FOR A CHANDELIER.

Application filed March 19, 1928. Serial No. 25,919. Term of patent 3½ years.

To all whom it may concern:

Be it known that I, MOSES C. ABUZA, a citizen of the United States, residing at Brooklyn, in the county of Kings and State of New York, have invented a new, original, and ornamental Design for a Body for a Chandelier, of which the following is a specification, reference being had to the accompanying drawing, forming a part hereof, in which the figure is an elevation view, slightly in perspective, showing my new design, the lighting elements and their connections being shown in dotted lines.

I claim:

The ornamental design for a body for a chandelier, as shown and described.

MOSES C. ABUZA.
